DESIGN FOR A HANDLE FOR SPOONS, &c.

Design No. 20,428, dated December 23, 1890.

UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 20,428, dated December 23, 1890.

Application filed November 17, 1890. Serial No. 371,743. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles for Spoons, Forks, Knives, Ladles, &c., of which the following is a specification, reference being had to the accompanying illustrations, forming part thereof.

Figure 1 is a photographic illustration of the obverse or front side of a spoon-handle, and Fig. 2 is a similar illustration of the reverse or bottom side of the same.

My design for the obverse side of the handle consists of a plain central panel *a*, inclosed by a waved marginal bead *b*, which crosses the handle at its wide end a short distance from the end. Outside this bead, at the end of the handle, is a series of bulbous forms *c* in relief, in the middle of which is a pair of balls *d*, one larger than the other, and connected by a stem to a bell-shaped flower *e*, extending over into the inner panel. At the point where the sides of the marginal bead converge and disappear there is filled in between the ends of said beads a train of balls *b* of graduated size, with a bell-shaped flower at the end next to the panel. The swelled portion of the handle between the shank and the bowl has an indented peak or point *g* running up from the curve of the bowl to a central bulb or ball,

and upon each side of the same are cat-paws *h*, formed by curved creases. On the reverse side a marginal waved bead *i* extends around the edge and incloses a panel, the bead terminating at the ends of the panel in small scrolls *m m'*. A bell-shaped flower *n* is joined centrally to the scroll at the wide end on the inside of the panel, and a similar flower *o* is joined to the scroll at the other end outside the panel, the figures all being in relief.

What I claim is—

1. The design for the obverse or front side of the handle, as herein shown and described. 45

2. The design for the reverse or back side of the handle, consisting of the marginal waved bead *i*, inclosing a panel and terminating at its ends in scrolls *m m'*, a bell-shaped flower *n*, joined centrally to the scroll at the wide end of the panel inside the same, and a similar flower *o*, joined to the scroll at the narrow end of the panel outside the same, as herein shown and described. 50

3. The design for the handles of spoons, &c., consisting of the ornamentalations *a b c d e f g h* on the obverse side and the ornamentalations *i m m' n o* on the reverse side, as herein shown and described. 55

AUSTIN F. JACKSON.
